108,324

DESIGN FOR A JAR

Edwin W. Fuerst, Toledo, Ohio, assignor to
Duffy-Mott Co., Inc., New York, N. Y., a corporation of New York

Application December 24, 1936, Serial No. 66,728

Term of patent 14 years

To all whom it may concern:

Be it known that I, Edwin W. Fuerst, a citizen of the United States, residing at Toledo, in the county of Lucas and State of Ohio, have invented a new, original, and ornamental Design for a Jar, of which the following is a specification, reference being had to the accompanying drawing, forming part thereof.

The single figure of the drawing is a perspective view of a jar embodying my new design.

The dominant features of the design comprise a jar of the outline shown having a plurality of abutting parallel convexed ribs, each extending entirely around the body of the jar from the bottom to the shoulder, the upper edge of

the uppermost rib merging into a concave neck which terminates in an enlarged annular bead rectangular in cross-section and of a diameter substantially equal to the upper edge of the uppermost rib; said jar being surmounted by a cap-receiving lip also rectangular in cross-section and of a diameter substantially equal to the diameter of the bottom of the jar, said lip and said bottom being approximately equally spaced from the portion of the body of the jar of largest diameter.

I claim:

The ornamental design for a jar substantially as shown and described.

EDWIN W. FUERST.
